ATTORNEY

UNITED STATES PATENT OFFICE

WENDELL A. MELTON, OF TULSA, OKLAHOMA, ASSIGNOR TO THE J. A. HULL CO., OF TULSA, OKLAHOMA

APPARATUS FOR INDUCING FLOW OF OIL FROM WELLS

Application filed September 25, 1928. Serial No. 137,741.

My invention relates to an apparatus for inducing the flow of fluids from wells and more particularly to use of an artificial pressure medium such as air or gas for inducing flow of liquid such as oil or water from the wells.

The principal objects of the invention are to so apply the artificial pressure medium as to supplement or assist the natural rock pressure within the well and to so confine the 10 artificial pressure medium above the existing rock pressure that it will not interfere with the natural flow of the fluids to the tubing by a back pressure against natural rock pressure existing in the well.

15 In accomplishing these and other objects of my invention I have provided improved details of structure, the preferred forms of which are illustrated in the accompanying drawing, wherein:

20 Fig. 1 is a vertical, sectional view through an oil well equipped with apparatus embodying my invention.

Fig. 2 is an enlarged, fragmentary, perspective view of the apparatus, parts being 25 shown in section to better illustrate the construction of the suction-creating nozzle, and

Fig. 3 is a similar view of a slightly modified form of apparatus.

Referring more in detail to the drawings 30 by numerals of reference:

1 designates a well hole having a liquid pocket 2 in an oil-bearing strata, the well hole being lined with the usual casing 4 supported upon the cap rock 5 by the casing shoe 6, all of which is in accordance with common practice and forms no part of the present invention.

35 Suspended within the casing 4 is a well tubing 7, having the usual perforations 8 at its lower end and extending at its upper end through a casing head 9, through which liquid is delivered from the pocket 2, both by rock pressure, which is usually present at the time the well is brought in, and later by 45 artificial means.

To assist or take the place of the natural rock pressure, I introduce a pressure medium such as air or gas, through a pipe 10 screwed into a nipple 11, on the casing head so that 50 the artificial pressure medium may be deliv-

ered into the casing and downwardly about the tubing near the lower end of the casing where its continued flow into the well pocket liquid strata is prevented by a packer 12 carried by the tubing and comprising rings 13 which engage the casing, thereby sealing off the natural rock pressure so that it may be effective to lift the fluid in the tubing and preventing back pressure on the liquid by the 55 artificial pressure medium.

Located within the tubing, immediately above the packer is a nozzle 14 comprising a swedged nipple 15 having a threaded lower portion 16 of a diameter to be received in the internally threaded ends 17 and 18 of adjoining tubing sections so that the nozzle is supported thereby and serves as a coupling for securing the tubing sections together. Above the threaded portion, the nozzle tapers inwardly to a reduced tubular portion 19 which 60 extends upwardly within the tubing to provide a circumferential restricted passageway 20 between the portion 19 and the walls of the tubing and which communicates with the annulus 21 between the tubing and casing 65 through a plurality of upwardly inclined openings 22 in the tubing, so that artificial pressure medium supplied to the casing through the casing head is directed upwardly about the mouth of the nozzle to draw liquid 70 from the nozzle by suction and force it upwardly within the tubing to delivery at the surface of the ground.

In employing the apparatus described, air or gas is forced under pressure through the 75 casing about the tubing until its flow is obstructed by the packer, and is directed upwardly through the openings in the tubing and about the nozzle, creating a vacuum therein to lift the liquid from the lower portion of the tubing and discharge it through the nozzle where it is picked up by the upwardly flowing air or gas and carried thereby to the upper end of the tubing from which it may be discharged into a storage 80 tank or like receptacle (not shown), without applying any back pressure on the producing strata.

85 In the modified form shown in Fig. 3, I employ a somewhat different type of nozzle 90

23 which is supported within the tubing by nipples 24 welded to the tubing and to the nozzle and providing communication between the interior of the nozzle and the space between the tubing and the casing. The nozzle 23 comprises a tubular body 25 similar to the nozzle in the preferred form and having a conical lower end 26 which does not interfere with free flow of liquid through the tubing, the upper end 27 of the nozzle terminating within a Venturi throat 28 formed within the tubing.

10 Thus it will be seen that in this form oil from the tubing will flow over the end of the nozzle and through the venturi, increasing the velocity of the flow through the tubing somewhat in the manner of an injector, and without applying back pressure on the producing strata.

15 20 What I claim and desire to secure by Letters Patent is:—

25 20 25 30 35 1. In combination with well casing, sectional tubing, two lower tubing sections having interior screw threads at their adjacent ends, said ends being in abutment, a nozzle having an exteriorly threaded body coupling said tubing sections to enclose the nozzle by the tubing and having an upwardly directed reducing nipple, the upper part of said tubing sections having upwardly inclined ports opening inwardly about the nipple, a packer between the tubing and casing below the ports, means for sealing the top of the casing, and means for delivering artificial pressure medium to the space between the tubing and casing above the packer.

40 45 50 2. Apparatus of the character described comprising a well casing, a tubing having a plurality of sections, a nozzle in the tubing, said nozzle having a nipple integral therewith and joining adjacent sections and a reduced portion joined to said nipple, a packer on the tubing below the nozzle in sealed relationship with the casing, the tubing having upwardly inclined openings surrounding the said reduced portion of the nozzle for admitting pressure medium from the space between the tubing and casing above the packer.

In testimony whereof I affix my signature.

50 WENDELL A. MELTON.
